(57) **CLAIM**

The ornamental design for an athletic compression shirt, as shown and described.

DESCRIPTION

FIG. 1 is a front, top and right-side perspective view of a sleeveless athletic compression shirt embodying my new design;

FIG. 2 is a rear, bottom and left-side perspective view thereof;

FIG. 3 is a front elevational view thereof;

FIG. 4 is a rear elevational view thereof;

FIG. 5 is a left-side elevational view thereof, the right-side elevational view being a mirror image;

FIG. 6 is a top plan view thereof;

FIG. 7 is a front, top and right-side perspective view of a long sleeve athletic compression shirt embodying my new design;

FIG. 8 is a rear, bottom and left-side perspective view thereof;

FIG. 9 is a front elevational view thereof;

FIG. 10 is a rear elevational view thereof;

FIG. 11 is a left-side elevational view thereof, the right-side elevational view being a mirror image; and,

FIG. 12 is a top plan view thereof.

The broken lines in the athletic compression shirt depict stitching and form no part of the claimed design.

1 Claim, 12 Drawing Sheets
